LIGHT FIXTURE

Paul J. Curtin, South Milwaukee, Wis., and Edward B. Smith, Jr., Arlington Heights, and Raoul E. Rodriguez, Chicago, Ill., assignors to McGraw-Edison Company, Milwaukee, Wis., a corporation of Delaware

Filed Sept. 8, 1960, Ser. No. 62,063

Term of patent 14 years

(Cl. D48—31)

FIG. 1 is a perspective of a light fixture embodying our new design;

FIG. 2 is a front elevation thereof;

FIG. 3 is a top plan view thereof; and

FIG. 4 is a bottom plan view thereof.

The dominant features of our design reside in the portions shown in full lines.

We claim:

The ornamental design for a light fixture, as shown and described.
